TRIGGER MECHANISM FOR MACHINE GUNS

Samuel G. Green, Gray, Ga.

Application January 16, 1935, Serial No. 2,027

3 Claims. (Cl. 89—27)

(Granted under the act of March 3, 1883, as amended April 30, 1928; 370 O. G. 757)

The invention described herein may be manufactured and used by or for the Government for governmental purposes, without the payment to me of any royalty thereon.

5 The subject of this invention is a trigger mechanism for machine guns.

Machine guns mounted on aircraft and adapted to fire between the blades of the propeller are operated by means of a trigger motor attached to the exterior of the gun casing and synchronized with the motor of the aircraft. The same type of gun is also mounted on other parts of the aircraft where synchronized firing is not required and it is also employed in tanks and armored cars. In these instances the gun is manually operated either directly or through remote control.

20 The purpose of this invention is to provide a hand trigger mechanism which may be readily interchanged with a right or left trigger motor without altering the standard equipment of the gun or interfering with its operative parts and which utilizes the attaching means of the trigger motor.

25 A further object is to provide an arrangement in which the trigger is maintained in a predetermined position longitudinally of the gun and is moved transversely and held in firing position by a positive and non-yielding structure.

30 To these and other ends, the invention consists in the construction, arrangement and combination of elements described hereinafter and pointed out in the claims forming a part of this specification.

35 A practical embodiment of the invention is illustrated in the accompanying drawing, wherein:

Fig. 1 is a view in side elevation of a machine gun equipped with the improved trigger.

Fig. 2 is a sectional view on the line 2—2 of Fig. 1, and showing the trigger in safe or inoperative position.

Fig. 3 is a similar view with the trigger in firing position.

Fig. 4 is a sectional view on the line 4—4 of Fig. 2.

45 Fig. 5 is a perspective view of the trigger.

Fig. 6 is a plan view of the trigger mechanism as shown in Fig. 2.

Figs. 7 and 8 are detail views of the trigger slide.

50 Fig. 9 is a sectional view of the trigger casing taken on the line 9—9 of Fig. 6.

Referring to the drawing by characters of reference, there is shown a machine gun of the Browning type whose breech casing consists of 55 spaced side plates 5—5 between which the usual

breech bolt 6 is reciprocally mounted. The bolt has a sear 7 which releasably holds a firing pin (not shown) and is moved by a transversely disposed sear slide 8 which is of the type employed in connection with the trigger motors of synchronized guns.

5 The side plates 5 are each formed with a pair of apertures 9—10 for mounting a trigger motor but in the present instance they are employed to mount the casing 11 of a hand trigger mechanism 10 by means of the conventional front cleat 12 and rear cleat 13, the latter being associated with a bolt 14, as is well understood in the art.

A trigger 15 disposed in an opening 16 in the casing has its front end pivotally mounted on a 15 pin 17 in the front part of the casing. The rear or free end of the trigger has lugs on opposite sides, the inside lug 18 having a cam surface 19 on its rear face and the outside lug 20 having a cam surface 21 on its front face. The trigger is 20 normally urged outwardly away from the gun by means of a coil spring 22 which is confined between the trigger and a web 23 of the casing 11.

The outer side of the casing 11 is formed with a longitudinally extending grooved channel 24 25 (Figs. 4 and 9) in which a slide 25, arranged substantially parallel to the trigger, is reciprocally mounted. The inside of the slide is formed with a recess 26 adapted to receive the lug 20 of the trigger and it has a cam surface 27 adapted 30 to coact with the cam surface 21 of the lug 20. A groove 28 is also formed on the inside of the slide and is spaced from the recess 26 to provide a solid surface 29. This groove receives a guide lug 30 on the outer side of the trigger. The lug 30 35 forms a seat for a spring 31 which is disposed in the groove 28 and serves to normally hold the slide in forward position.

For purposes of convenient assembly, the spring 31 is seated on the lip 32 of a plate 33 which is 40 part of the slide, being attached thereto by a bolt 34 having a collar 35 engaging the plate. A pin 36 on the lip 32 is disposed within the spring 31 and thereby holds the front part of the plate in place.

45 The inner face of the plate 33 is provided with a lug 37 which is accommodated in a groove 38 in the slide and has its opposite ends riding in slots 39—39 in the opposite rails forming the channel 24 of the casing 11. As clearly seen in 50 Fig. 6 the lug 37 serves as a stop member to limit reciprocation of the slide and plate with respect to the casing 11.

The slide is retracted by acting on the bolt 34 either directly or through a cable 30. The slide 55

is normally held in the forward or inoperative position (Fig. 2) by the spring 31. In this position the trigger is urged outwardly by the spring 22 to dispose the lug 20 in the recess 26 of the 5 slide with the cam surfaces 21 and 27 in contact.

On retraction of the slide 25 the trigger is cammed inwardly towards the gun and is positively held in the firing position with the lug 20 seated on the solid surface 29 of the slide as 10 shown in Fig. 3. When the slide is released the parts assume the positions shown in Fig. 2.

In continuous firing the trigger is held in the firing position while the breech bolt is reciprocating. On the forward stroke the bolt approaches 15 battery with the sear slide 8 in the cocked position shown in Fig. 2 and when it is almost home the slide 8 engages the cam surface 19 of the lug 18 and is moved inwardly to release the sear. The position of the trigger longitudinally of the 20 gun is always the same and the sear slide 8 will always be actuated at a predetermined position in the travel of the bolt which position is just before the bolt is home. The impact of the sear slide 8 on the trigger will not vary its position 25 and it will not be transmitted to the slide 25.

I claim:

1. In a trigger mechanism, a casing adapted to be attached to a gun and having an aperture and a channel, a trigger pivotally mounted in the

casing with its free end arranged to move through the aperture therein, lugs on opposite sides of the free end of the trigger, the lug on the inside of the trigger having a cam surface on its rear face and the lug on the outside of the trigger having 5 a cam surface on its front face, a slide mounted in the channel of the casing substantially parallel to the trigger and having a recess with a cam surface adapted to coact with the cam surface on the outer lug of the trigger, and a spring 10 seated on the trigger and acting on the slide to normally hold it in forward position.

2. In a trigger mechanism, a casing adapted to be attached to a gun, a trigger pivotally mounted in the casing and having a lug intermediate its 15 ends a slide mounted in the casing substantially parallel to the trigger and having a groove for receiving the lug of the trigger, a spring confined between the lug of the trigger and the slide, and means on the slide for displacing the trigger. 20

3. In a trigger mechanism, a casing adapted to be attached to a gun and formed with channel members having opposite slots, a trigger-actuating slide mounted in the channel and having a recess, and a plate secured to the slide and having a lug extending across the recess in the slide and riding in the slots of the channel members of the 25 casing.

SAMUEL G. GREEN.
